[57] CLAIM

The ornamental design for a display box for watches and accessories, as shown and described.

DESCRIPTION

FIG. 1 is a perspective view of my new design for a display box for watches and accessories;

FIG. 2 is a perspective view thereof with the cover open and the accessories removed for convenience of illustration;

FIG. 3 is a top view of the design of FIG. 2 showing a top lid in a closed position;

FIG. 4 is a perspective view of the design of FIG. 1 with the support pieces shown outside the case on a larger scale; and, FIG. 5 is a bottom view of the design of FIG. 1.
